THREAD GRINDING MACHINE

Fernand Turrettini, Geneva, Switzerland, assignor to Societe Genevoise d'Instruments de Physique, Geneva, Switzerland, a firm of Switzerland

Application May 8, 1944, Serial No. 534,584
In Switzerland November 27, 1943

1. Claim. (Cl. 51—95)

This invention relates to a thread grinding machine wherein the work piece carrying table supporting a device for truing the grinding wheel is operated by means of a lead-screw cooperating with a nut, the bed of the machine comprising two abutments determining two positions of the table: one for the grinding of the work piece and the other for the truing of the grinding wheel. According to the invention, this machine is characterized by an auxiliary slide arranged movably on the bed, and inserted between the nut and one of the abutments mentioned above, by a system of two unequal counterweights exerting their action in opposite directions on the auxiliary slide, and by lifting means enabling to temporarily remove the action of the heavier counterweight on the auxiliary slide, the whole being arranged in such a manner that the action of the counterweights either maintains the auxiliary slide in contact with the first abutment during the grinding operation or brings the table into contact with the second abutment for truing the grinding wheel.

The annexed drawings represent by way of example an embodiment of the invention. Fig. 1 is a sectional elevation and Fig. 2 a transversal section. Fig. 3 is a view in perspective in which the table, as well as the front face of the bed have been omitted in order to show the mechanism.

In any of these figures 1 is the table movable on the guide ways 28 and 28a of the bed 6. 2 is the spindle and 2a the headstock, 3 the tailstock, 4 the truing device, 5 the grinding wheel, 6 the bed and 7 the abutment fixed to the bed, which determines the truing position of the table; 8 is a train of reduction gears connecting the spindle to the lead-screw 9; 10 and 10a are the lead-screw bearings, 11 is the lead-screw nut, and 12 an auxiliary slide; 13 is a groove in the bed for guiding the auxiliary slide 12. 14 is the face of the nut 11 which bears against two brackets 20 and 20a dependent on the auxiliary slide 12 and located on each side of the lead-screw 9. 15 and 15a are two lateral trunnions of the nut 11 to which are attached the cables 16 and 16a passing over the pulleys 17 and 17a. These cables are supporting the first counterweight 19, the heavier out of the two. 20 is a cable used for lifting the counterweight 19 and being wound-up on a winding drum 21 by means of a handle 22. 23 is the abutment of the bed, determining the grinding position of the table, abutment against which the auxiliary slide 12 comes to rest under the action of the counterweight 19 during the grinding operation; 18 are brackets forming part of 23 and bearing the pulleys 17 and 17a. 24 are the bolts for fixing of 23 on the bed 6. 25 is the cable connecting the auxiliary slide 12 to the second coun-

terweight 27 (the less heavy out of the two), by passing over the pulley 22. 28 is a finger dependent on the nut 11 and engaging in a recess 31 of the auxiliary slide 12, this in order to prevent said nut from rotating. This nut 11 could be maintained in position by using other means—to prevent it from rotation. When the grinding work is being performed, all the parts are in the position shown on the drawings.

- 10 19 is attached to the cable 20 has to be lifted by means of the winding drum 21 and the handle 22. In this case the counterweight 27 is going to pull the auxiliary slide 12 towards the left, which, in its turn, will move the table towards the left, by means of the parts 11 and 9, and this until the table comes into contact with 7. Now the truing device 4 will be in the working position in front of the grinding wheel 5.
- 15 20 This operation may be carried out very rapidly by giving the handle 22 a few turns. This handle must be immobilised by means not represented in the drawings, when the counterweight 19 is supported by the winding drum 21, in order to prevent the lowering of the counterweight 19 before the truing of the grinding wheel is completed.

25 Obviously it is of importance to reduce to a minimum the friction of the auxiliary slide 12 and of the table 1 on the bed 6 in order to decrease the necessary weight difference between the counterweights 19 and 27. This purpose can be achieved either by arranging the table to rest on a few points 29 only on the slideways of the bed, or by making it roll on these slideways.

- 30 35 What I claim is:
- In a thread grinding machine with a work piece-carrying table supporting a device for truing the grinding wheel and being operated by means of a lead-screw cooperating with a nut, the bed of the machine comprising two abutments determining two positions of the table: one for the grinding of the work piece and the other for the truing of the grinding wheel, in combination, an auxiliary slide arranged movably on the bed and inserted between the nut and one of the abutments, a system of two unequal counterweights exerting their action in opposite directions on the auxiliary slide, and lifting means for temporarily rendering the heavier counterweight ineffective whereupon the auxiliary slide is moved by the lighter counterweight, the whole being arranged in such a manner that the action of the counterweights either maintains the auxiliary slide in contact with the first abutment during the grinding operation or brings the table in contact with the second abutment for the truing of the grinding wheel.

FERNAND TURRETTINI.
